UNITED STATES PATENT OFFICE.

OTTO C. WINESTOCK, OF PERKINSVILLE, VERMONT.

METHOD AND APPARATUS FOR DEFIBERING PAPER AND LIKE MATERIALS.

Application filed November 29, 1924. Serial No. 752,977.

To all whom it may concern:

Be it known that I, OTTO C. WINESTOCK, a citizen of the United States, residing at Perkinsville, in the county of Windsor and State of Vermont, have invented certain new and useful Improvements in Methods and Apparatus for Defibering Paper and like Materials; and I do hereby declare the following to be a full clear, and exact description of the invention, such as will enable others skilled in the art to which it appertains to make and use the same.

The invention relates to a method and apparatus for defibering paper and like materials to render the fibers available for reuse, and has for its object a maximum recovery of fiber stock with a minimum of labor and expense and practically no impairment of the fibers, so that the latter are available for any of the various applications to which the original stock is adapted. To these ends, the invention comprises immersing the material in a liquid medium and subjecting the mixture to rapid and constant reversals of movement within the mass, by the application of rapidly reversed forces of substantially equal intensities and opposite directions, these operations preferably being carried out in a continuously operating machine, including a closed casing, provided with means for feeding the paper stock and the liquid thereto at one end and delivering the defibered stock from the opposite end, and a series of rapidly moving blades of alternating opposite pitch in the casing, for producing rapid and constant reversals of movement of the paper stock within the mass, which will be effective in loosening and separating the fibers without rupturing or impairing the individual fibers, and also in dislodging and separating ink or other foreign matter from the fibers, the deinking and cleansing operation being materially facilitated by combining with the immersing liquid a suitable detergent or cleansing agent.

Apparatus for carrying out the method is illustrated in the accompanying drawings, in which:

50 Fig. 1 is a side elevation of a simple and typical defibering machine.

Fig. 2 is a sectional end elevation of the same.

55 Fig. 3 is a plan view of the machine with the cover removed.

It has been proposed heretofore to defelt

or defiber paper and like materials by immersing the material in relatively large volumes of water, containing a suitable detergent, and subjecting the material, while immersed in the liquid, to opposite forces tending to pull the material apart, one of which forces is the inertia of the liquid in which the paper is suspended, the operation being carried out in a circulatory apparatus, including a straight cylindrical tube in which one or more rapidly revolving propeller blades are mounted, the speed of rotation of the blades being sufficient to cause cavitation within the liquid medium, the moving blades serving to exercise a pulling force on the fibers of the paper, which force is resisted by the inertia of the liquid in which the paper is suspended, the resultant of the two forces being ultimately effective in loosening and separating the individual fibers. In order to effect the operation, the mixture of liquid and paper stock is forced in a circulatory path repeatedly through the chamber or tube containing the propelling elements, so that the apparatus is open to the objection that it is periodic and not continuous in operation, and the method has been found to be commercially inefficient, because of the very large amount of power required to circulate the large body of water containing a relatively small proportion of paper to be defibered, and also because of the length of time required to effect the defibration of a single batch. The relatively large proportion of water required in carrying out this old method of defibering is necessary, in order to produce the requisite element of inertia to resist or retard the tendency of the paper to move with the impelling blades. Inasmuch as the inertia of the liquid in which the paper is suspended or immersed is necessarily very much less than the force produced by the rotatitng blades tending to move the elements of the paper in opposition to the force of inertia of the liquid, it will be apparent that these two forces will necessarily have to be applied repeatedly to the paper stock to loosen and separate the fibers. These two factors, to wit, the very large amount of energy required to circulate the excessive proportion of water as compared with the paper stock to be defibered, and the time interval necessary to subject the fibrous mass to repeated applications of the force developed by the propeller and the opposing force of inertia

of the liquid, render the old method objectionable, because of the expense involved, and it is for this reason that the former method and apparatus aforesaid have not 5 proved commercially successful.

The instant invention is commercially feasible and practically efficient for the reason that the method can be carried out at an expenditure of a minimum of energy and in 10 a minimum of time per unit volume of paper stock defibered. Moreover, the application of the method and the operation of the mechanism is continuous, so that the output of defibered stock per machine is vastly increased over that of the machines of the 15 older types. Moreover, the machines for carrying out the method may be constructed of relatively small size, few and simple parts, which are not liable to undue wear or impairment, and which may operate continuously 20 without the attention of highly skilled labor.

Referring to the drawings, which show a typical machine that has proven effective in 25 defibering various types, grades and forms of paper and paper stock, 1 indicates the lower portion of a casing, to which is secured a generally similar shaped upper section 2, the two sections defining an interior 30 chamber generally rectangular in horizontal cross section and having a transverse section of two intersecting circles. The bottom section is provided with an integral base or standard 1' and the two sections are 35 secured together in liquid tight relation by means of the lateral mating lugs 3 and 4, which are connected together by screw bolts 5. The end walls of the casing are provided with journal bearings 6 and 7 and 6' and 7' 40 preferably provided with anti-friction elements to support longitudinal shafts 9 and 11, which are provided with suitable packing glands to prevent leakage. Each shaft is equipped with a series of propellers disposed in longitudinal series thereon and 45 rigidly secured thereto to rotate with the shafts. The blades on each propeller are alternately of opposite pitch. As indicated, the blades 12 of propellers 10 on shaft 9 are 50 alternately of right hand and left hand pitch and the blades 14 of propellers 13 are similarly arranged, that is to say, the right hand blades are interposed between the left hand blades. For most effective operation, the 55 propellers are arranged in relatively close series on the shafts and are of such diameter as to fit within the casing with a relatively slight peripheral clearance, the supporting shafts being so disposed that the 60 blades of the propellers on said shafts overlap each other in certain portions of their rotary movement, as clearly illustrated in Figs. 2 and 3.

The forward part of the casing is 65 provided with a hopper 16, the discharge end

of which is in communication with the inlet opening 17 of the casing, the forward part of the casing immediately below the inlet opening being clear, to provide a chamber to receive the mixture of paper stock and liquid before the latter is operated upon by the propellers. Discharging into the upper part of the hopper 16 is a pipe 18 for continuously delivering the paper stock to the hopper. The hopper is also supplied with a 75 water supply pipe 19 and a pipe 20 for delivering a detergent or cleansing medium to the hopper.

The rotary shaft 9 and 11 are preferably 80 separately driven in the same direction by suitable high speed motors, as for example the steam turbines 30 and 31, as illustrated in Fig. 1, although, obviously, the shafts may be driven by a single motor unit or from any other suitable source of power. 85

In carrying out the new method, the paper stock is preferably roughly torn into sections or fragments and dusted and fed to a tank containing either cold or warm water 90 in which operates a suitable shredding or tearing device, which reduces the mass of paper to pieces of approximately uniform size, averaging about one square inch in superficial area, for example. The mass of paper and water is quite dense, as a relatively small proportion of water as compared with the amount of paper, is sufficient for all phases of the operation. The preliminary shredding of the paper may be effected 95 by any of the various types of apparatus designed for this purpose. This prepared stock is then fed continuously to the defibering machine by the discharge pipe 18 leading from the preliminary shredding apparatus to the hopper 16, and with an additional supply of water at approximately 150 degrees Fahrenheit by pipe 19 and a measured quantity of suitable detergent or cleansing medium, such as soap water or soap water 100 and soda ash in solution, or other suitable alkaline cleaner for the purpose of cleaning the paper fibers of ink particles, stains and other foreign material fed to the hopper by pipe 20. As indicated, the mixture of shredded paper stock and liquid is quite dense, as the liquid carries a very much larger proportion of paper stock than was feasible with the older methods of defibering such stock. When the defibering chamber has been practically filled with a mixture of stock and the liquid in which the stock is immersed and the propeller shafts are driven at a speed from 2500 to 4000 R. P. M., according to the character and texture of 110 the paper stock, there is set up within the machine and within the mass represented by the stock and the water of submersion a multiplicity of forces substantially equal in intensity and opposite in direction, produced 115 by the blades of opposite pitch on the individ-

- ual propellers and the coaction of the corresponding blades on adjacent propellers on the same shaft and also on adjacent propellers on the companion shaft, these equal and opposite forces being constantly and rapidly reversed in direction, which produces a rapid and constant reversal of the motion of the stock, the effect of which is to quickly loosen and separate the individual fibers.
- 5 In other words, the individual fibers are pulled from the mass by the application of an opposition of forces, which are rapidly reversed due to the alternating reverse pitch of the blades of each propeller and the like 70
- 10 alternating reverse pitch of the corresponding blades of adjacent propellers either on the same shaft or on the companion shaft, which, as indicated, is driven in the same direction. In addition to the positive and 75
- 15 opposing forces applied to the fibers of the paper stock, a violent interruption and reversal of the direction of movement of the paper stock in the submerged liquid sets up a commensurably strong vibratory movement 80
- 20 of the felted mass of fibers constituting the paper stock, which is most effective in loosening up the fibrous mass, and thereby materially assisting the opposing and rapidly reversed forces imposed on the individual 85
- 25 fibers by the action of the propeller blades, as described.
- As indicated, the paper stock and the necessary liquid, consisting of warm water or warm water and the cleansing agent, are 90
- 30 fed constantly to the machine by gravity, so that the defibering operation is continuous, the defibered stock and the liquid being discharged continuously from the outlet 15 at the rear of the machine. At no point in the 95
- 35 operation of the apparatus, are the mechanical means for producing the rapid reversal of the forces operating on the stock employed to forward the stock or feed the same through the machine, as the discharge of the 100
- 40 defibered stock and the liquid in which the latter is submerged is effected by the hydrostatic head of the mixture in the hopper 105
- 45 16, and as this can be readily regulated, it is apparent that the operation of the machine may be so timed as to defiber stocks of 110
- 50 various characters, consistencies and textures. In other words, by regulating the speed of the propeller shafts and the normal rate of flow of the liquid and stock through 115
- 55 the machine, an effective and complete defibration of any character of stock may be accomplished in a minimum of time. Because of the fact that the only mechanical power required is that necessary to drive 120
- 60 the propeller shafts, and inasmuch as the propellers are not employed to move the mass of water and stock through the machine, it will be apparent that the machine 125
- 65 can be operated at a minimum expenditure of mechanical energy. It will be under- 130
- stood, therefore, that while the elements for producing the rapid reversal of opposing forces and the abrupt change of direction of flow in the mass of paper stock and liquid are defined as propeller blades, they do not, in any sense, operate as means for propelling or forcing the mass of stock and liquid through the machine.
- While relatively warm water may be advantageously employed with certain types of stock, it is not essential that the water be warmed, as, in many cases, water at ordinary temperature, or even cold water, may be used with good effect. Likewise a relatively mild detergent or cleansing agent, of the character indicated, may be employed, which will completely avoid the weakening or impairment of the fibers, which is an evil common to the ordinary detergents employed in deinking paper stock 85 heretofore.
- As indicated, the operation of the mechanism and the process is continuous and no mechanical power is required to force large volumes of water in a circulatory path 90
- through the machine, as has been necessary in the former types of apparatus, and the thoroughly and completely defibered, deinked and cleaned stock is delivered from the machine continuously, where the recovered pulp may be passed directly to suitable rinsers or pulp washers, after which the mass of fibers or pulp is available for any use to which the original fibers or pulp mass 100
- was adapted, as, for example, for immediate reworking into paper or collecting in the form of pulp stock for subsequent use, as will be understood.
- While the propellers have been shown, in the exemplary machine, as having blades alternating in pitch, it will be understood that the apparatus will operate effectively if each propeller of the series is provided with blades having the same inclination or direction of pitch, the blades of alternating propellers being of opposite pitch, which will have the effect of developing forces of equal intensities and opposite directions between coacting blades of successive propellers.
- When the paper stock is to be deinked and cleaned as well as defibered, it is desirable to use warm water, which is fed, together with the detergent, directly to the defibering machine with the paper stock from the hopper, and as the amount of water relatively to the paper stock is much less than that heretofore required, it will be apparent that a material saving is effected in heating the relatively small quantity of water, as compared with the heavy cost of heating the very large volumes of water required in the old practice, and the tendency of the fibers to impairment, due to exposure to hot water for a considerable length of time, is obviated.

What I claim is:

1. The method of defibering paper and similar materials which comprises immersing the material in a liquid, and subjecting the material to the action of substantially equal and opposite forces of the same character transmitted through the liquid and of sufficient intensities to separate the fibers. 65
2. The method of defibering paper and similar materials which comprises immersing the material in a liquid, and subjecting the material to the action of substantially equal and opposite rotary forces transmitted through the liquid and of sufficient intensities to separate the fibers. 70
3. The method of defibering paper and similar materials which comprises immersing the same in liquid and subjecting the mass to the action of rapidly reversed forces of substantially equal intensities and opposite directions and of sufficient intensities to separate the fibers. 75
4. The method of defibering paper and similar materials which comprises immersing the same in liquid and subjecting the mass to the action of rapidly reversed rotary forces of substantially equal intensities and opposite directions and of sufficient intensities to separate the fibers. 80
5. The method of defibering paper and similar materials which comprises comminuting the material, immersing the same in liquid and subjecting the mass to the action of rapidly reversed forces of substantially equal intensities and opposite directions and of sufficient intensities to separate the fibers. 85
6. The method of defibering paper and similar materials which comprises comminuting the material, immersing the same in liquid and subjecting the mass to the action of rapidly reversed rotary forces of substantially equal intensities and opposite directions and of sufficient intensities to separate the fibers. 90
7. The method of defibering paper and similar materials which comprises immersing the material in a relatively small amount of liquid and subjecting the mass to the action of substantially equal and opposite forces of the same character and of sufficient intensities to separate the fibers, and rapidly reversing the directions of said forces. 95
8. The method of defibering paper and similar materials which comprises immersing the material in a relatively small amount of liquid and subjecting the mass to the action of substantially equal and opposite forces of the same character and of sufficient intensities to separate the fibers, and continuously reversing the directions of said forces. 100
9. The method of defibering paper and similar materials which comprises immersing the material in liquid and passing the mass between propelling elements developing substantially equal and opposite forces of like character in the mass and of sufficient intensities to separate the fibers. 105
10. The method of defibering paper and similar materials which comprises immersing the material in liquid and passing the mass between rotary propelling elements developing substantially equal and opposite forces of like character in the mass and of sufficient intensities to separate the fibers. 110
11. The method of defibering and deinking paper and like materials which comprises immersing the material in a liquid containing a detergent and subjecting the mass to the action of rapidly reversed forces of substantially equal intensities and opposite directions and of sufficient intensities to separate the fibers. 115
12. The method of defibering and deinking paper and like materials which comprises flowing the material and a liquid in a continuous volume and effecting rapidly recurring and constant reversals of movement of the material within the mass. 120
13. Apparatus for defibering paper and like materials comprising a casing, a hopper for feeding the material and a liquid to one end of the casing, a discharge outlet at the opposite end of the casing, and movable blades of opposite pitch operating in said casing to effect rapidly recurring and constant reversals of movement of the material within the mass. 125
14. Apparatus for defibering paper and like materials comprising a casing, a hopper for feeding the material and a liquid to one end of the casing, a discharge outlet at the opposite end of the casing, a rotary shaft mounted in the casing, and propeller blades of alternating opposite pitch on said shaft to effect rapidly recurring and constant reversals of movement of the material within the mass. 130
15. Apparatus for defibering paper and like materials comprising a casing, a hopper for feeding the material and a liquid to one end of the casing, a discharge outlet at the opposite end of the casing, parallel rotating shafts mounted in the casing, and propellers on the shafts, the successive blades on each propeller and the corresponding blades of the successive propellers being of opposite pitch. 135

In testimony whereof I affix my signature.
OTTO C. WINESTOCK.
